(57) **CLAIM**

The ornamental design for a display screen with graphical user interface, as shown and described.

DESCRIPTION

FIG. 1 is a front view of a first image in a sequence for a graphical user interface;

FIG. 2 is a front view of a second image thereof;

FIG. 3 is a front view of a third image thereof;

FIG. 4 is a front view of a fourth image thereof;

FIG. 5 is a front view of a fifth image thereof;

FIG. 6 is a front view of a sixth image thereof;

FIG. 7 is a front view of a seventh image thereof;

FIG. 8 is a front view of an eighth image thereof;

FIG. 9 is a front view of a ninth image thereof;

FIG. 10 is a front view of a tenth image thereof; and,

FIG. 11 is a front view of an eleventh image thereof.

The appearance of the graphical user interface sequentially transitions between the images shown in FIGS. 1-11. The process or period in which an image transitions to another forms no part of the claimed design.

The outermost broken lines showing a mobile device illustrate environmental subject matter and form no part of the claimed design. The remaining broken lines showing a display screen and elements of the graphical user interface illustrate portions of the article that form no part of the claimed design.
